UNITED STATES PATENT OFFICE

JAMES L. RUBEL, OF CHICAGO, ILLINOIS, ASSIGNOR TO APEX STAMPING COMPANY, OF CHICAGO, ILLINOIS, A CORPORATION OF ILLINOIS

DESIGN FOR A TOY AEROPLANE

Application filed March 6, 1929. Serial No. 30,373. Term of patent 14 years.

To all whom it may concern:

Be it known that I, JAMES L. RUBEL, a citizen of the United States, residing at Chicago, in the county of Cook, State of Illinois, have invented a new, original, and ornamental Design for Toy Aeroplane, of which the following is a specification, reference being had to the accompanying drawing, forming

a part hereof, wherein the figure is a perspective view of a toy aeroplane, showing my new design.

I claim:

The ornamental design for a toy aeroplane, as shown.

JAMES L. RUBEL.
